TYPEWRITING AND ACCOUNTING MACHINE

Elmer L. Wise, Bridgeport, Conn., assignor to Underwood Elliott Fisher Company, New York, N. Y., a corporation of Delaware

Application May 16, 1941, Serial No. 393,738

3 Claims. (Cl. 235—59)

This invention relates to combined typewriting and accounting machines of the type in which the numbers are entered digit by digit in the register or registers.

In the operation of such machines, operators are often paid by the entry or line. When operators are paid on this basis, it is important to be able to obtain the total of the number of entries or lines without going through the tedious and laborious time-consuming operation of counting these from the finished work sheets.

One object of the present invention is to produce a counting device for machines of the above class which will count the entries made or lines typed on each work sheet as the sheets are typed.

Another object of the invention is to devise a counting device for counting the lines typed or entries made upon a machine of the above class which may be applied to existing machines with minimum changes in the structures of the machines.

With the above objects in view, the invention consists in a mechanism embodying the novel and improved features, constructions and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings—

Fig. 1 is a view in side elevation with certain parts broken away and certain parts shown in section, illustrating a portion of a typewriting and accounting machine with the invention applied thereto.

Fig. 2 is a plan view illustrating the column registers of the machine and certain associated parts, with certain elements of the counter mechanism removed from the left hand register.

Fig. 3 is a detail view in rear elevation illustrating one of the column registers shown in Fig. 2, with a counter mechanism embodying the invention applied thereto, and

Fig. 4 is a detail view in rear elevation illustrating the register engaging cam mechanism.

The invention is illustrated in this application as applied to a combined typewriting and accounting machine of the so-called Elliott Fisher type. The machine preferably has substantially the same general construction, arrangement and mode of operation of parts as the machine illus-

trated and described in the patent to Foothorap No. 1,904,127, dated April 18, 1933. The machine comprises a rectangular platen frame, one of the side bars or rails of which is indicated at 2 and a substantially flat platen indicated at 4 mounted for vertical movement in said frame. A line space frame, a portion of which is indicated at 6, is mounted for forward and rearward movement on the side rails of the platen frame, and is provided with front and rear rails 8 and 10 upon which are mounted for movement in letter spacing direction and return, a type carriage, a portion of which is indicated at 12, said carriage being provided with rolls 14 and 16 arranged to engage respectively the front and rear rails 8 and 10 of the line space frame. Upon the carriage 12 are mounted a series of key levers, one of which is indicated at 18, for actuating the type bars (not shown) to engage the types with the work sheets 20 resting on the surface of the flat platen 4. These key levers include certain numeral key levers which are arranged to control not only the impression of the numeral type on the work sheets, but also, under certain conditions, the actuation 25 of certain register mechanisms to enter numbers in the registers.

The register actuating mechanism comprises a master wheel 20 mounted on the type or key carriage 12 and arranged to operate the accumulator 30 mechanism of the column registers. The master wheel 20 may be actuated manually from the key levers through a differential mechanism such as that shown and described in the patent to Foothorap No. 1,576,760, dated March 16, 1926, or said wheel may be actuated by power operated mechanism controlled by the key levers such as that shown in the application of Oscar J. Sundstrand, Serial No. 281,772, filed June 29, 1939.

As illustrated in this application, the machine 40 is provided with a plurality of column registers indicated at 22 mounted on a supporting rail 24 carried by the uprights 26 of the line space frame. These registers are each clamped in fixed position on the rail 24 by means of the usual clamping device 28 actuated by a knurled hand wheel 30. The registers are each located in a definite position longitudinally of the rail 24 by means of a locating lever 32 arranged to engage in any one of a series of openings 34 in the rail.

Each of the registers illustrated has substantially the same construction and mode of operation of parts as the register illustrated and described in the patent to Foothorap No. 1,994,639, dated March 19, 1935, although registers having any other suitable construction may be employed.

The accumulator mechanism of the register comprises a series of number wheels 36 connected by suitable idle gears 38 with the value wheels 40. The number wheels 36 are arranged side by side upon the shaft 42 to represent the different denominations and the master wheel 20 is moved into and out of meshing engagement with the number wheels and is transferred from denomination to denomination thereof by the letter spacing movement of the carriage 12.

Each column register is provided with a transfer mechanism indicated generally at 44 and having substantially the same construction as the transfer mechanism shown and described in Foothorap Patent No. 1,994,639, referred to above. The drawings show the transfer mechanism in its normal or untripped position. After being tripped by the entering of numbers in the register during the advance movement of the type carriage, the transfer mechanism is reset during the return movement of the carriage to carry the master wheel past the register. The reset mechanism comprises a slide indicated at 46 mounted for forward and rearward movement on the base 48 of the register and connected with the transfer mechanism 44 by a restoring means such as illustrated and described in said Foothorap Patent No. 1,994,639. The slide 46 normally occupies the forward position with relation to the column register shown, in the case of the right hand register, in Fig. 2. During the return movement of the carriage, a roll 50 mounted on the forward end of the slide is engaged with a cam 52 mounted on the carriage and the slide is moved rearwardly to restore the transfer mechanism. When the roll 50 passes the cam 52, the slide 46 is moved back to its forward position by the action of the coiled spring 54. This spring is attached to a gear segment 56 pivoted on a shaft 58 fixed at its ends in the side plates of the column register. The gear segment meshes with a gear 60 journaled on a shaft 62 also fixed at its ends in the side plates of the register and said gear meshes with gear teeth 64 formed on the upper side of the slide 46.

The cam 52 is mounted on the usual cam lever 66 pivoted at 68 on the type head or carriage and is depressed below the slide 46 during the advance of the carriage to by-pass the slide. When the carriage is advanced to carry master wheel 20 beyond the last denomination of the register, the cam lever 66 is swung upwardly to its normal position by the action of a suitable spring. The position of the cam lever 66 is controlled by mechanism such as that disclosed in the patent to Foothorap No. 2,145,254, dated January 31, 1939, and in the co-pending application of Oscar J. Sundstrand, Serial No. 281,772, filed June 29, 1939. This mechanism will be briefly described herein.

The cam lever 66 is provided with a slot which receives the end of an arm on a lever 72 pivoted on the stud 74 on the type carriage. The lever 72 is acted upon by a coiled spring 75 which tends to swing the same and the cam lever 66 upwardly and the upward movement of said levers under the action of said spring is limited by a pin 77. The lever 72 is connected by a coiled spring 76 with the register engaging cam lever 78 also pivoted on the stud 74. This cam lever is provided with the usual cam 80 which is engaged and depressed to depress the cam lever 78 by a rounded surface formed on the lower part of the left side (Fig. 2) of a plate 82 secured to the base of the register upon movement of the

carriage into the zone of a register. The cam lever 78, in its downward movement, swings the lever 72 and thereby the cam lever 66 downwardly therewith by the engagement of an arm 84 formed on the cam lever with an eccentric stop 86 secured to the lever 72.

Thus, through the connections described, when the register engaging cam 80 is depressed by the forward movement of the carriage to locate the master wheel on the type carriage in the zone of a register, the cam lever 66 is depressed below the reset slide 46 and will have no action on said slide during the advance movement of the carriage to carry the master wheel past the zone of the register. Upon the return of the carriage, however, the cam 80 on the lever 78 travels over the upper side of the plate 82 so that the cam lever 66 is not depressed and will act on the slide 46 to move the same rearwardly.

The counter for counting the return movements of the type carriage indicated at 88 is mounted on the left hand one of the two column registers as shown in Figs. 1 and 2. The counter is of the kind or type in which the counter mechanism is operated by the oscillation of the main shaft of the counter and may have any suitable construction to effect this result. For example, the counter may have substantially the same construction as the counter illustrated and described in the patent to Veeder, No. 1,873,079, dated August 23, 1932. In Figs. 4 and 5 of this patent, is illustrated a construction in which the counter mechanism is actuated by the oscillation of an actuating lever mounted on the main shaft of the counter.

In the construction shown, the counter is provided with a base plate 90 fixed by suitable screws 91 to the upper portion of an attaching plate 92. This latter plate has an angular formation shown clearly in Fig. 1 and the lower portion thereof is secured by screws 94 to the rear wall 96 of the register. The upper portion of the attaching plate 92 is offset with relation to the lower portion thereof, as shown in Fig. 3, to enable certain parts of the operating mechanism to be aligned as will be later described.

To the main shaft 98 of the counter is attached an arm 100 projecting downwardly therefrom and the arm is oscillated to actuate the counter during each return movement of the type carriage by mechanism connected with the rear end of the transfer restoring slide 46. The arm 100 normally occupies the position shown in Fig. 1 in engagement with a suitable stop 101 secured to the boss 103 on the counter. The arm is swung in a counter-clockwise direction, Fig. 1, upon each return of the carriage of the machine to actuate the counter mechanism. After each counter-clockwise movement, the arm is returned to the position shown in Fig. 1 by a coiled spring 105.

To the rear end of the slide 46 is fixed a bracket 102 formed with a slot 104 in which engages a pin 106 mounted on the lower end of an oscillatory lever 108 pivoted on a stud 110 secured in a supporting block 112 fixed to the lower portion of the attaching plate 92. The lever 108 is formed at its upper end with a slot 114 in which engages a pin 116 secured to the lower end of a second oscillatory lever 118 pivoted on a stud 120. This stud is supported on the rear end of a supporting lever 122 pivotally adjustable on a stud 124 fixed in a supporting bracket 126 secured to the upper side of the casing of the register by screws 128. The lever 118 carries at its upper end a pin 130 arranged to engage the oscillatory arm 100.

of the counter to swing said arm in a counter-clockwise direction, Fig. 1.

The lever 122 is arranged to be adjusted in the position shown in full lines in Fig. 1 or in the position shown in dotted lines in said figure to locate the lever 118 either in the full line or in the dotted line position shown in said figure, the lever 122 having a rounded projection on one side thereof arranged to engage alternatively in the opposed recesses 132 and 134 in a plate-like extension formed on bracket 126 to hold the lever respectively in said positions. The levers 108 and 118 are each given a complete oscillating movement during each rearward and forward movement of the slide 46 imparted to the slide during each return movement of the carriage from a position in which the master wheel 20 is located to the right of the left hand register to a position in which the master wheel is located to the left of said register. With the lever 122 adjusted in the position shown in full lines in Fig. 1, the lever 118 is located in position to cause the pin 130 to engage the arm 100 during each oscillation of the lever and impart a corresponding oscillation to said arm and thereby actuate the counter mechanism to add one therein. The lever 118 is adjusted in this position when it is desired to count each return movement of the carriage. When it is desired that the counter mechanism shall be rendered inoperative, the lever 118 is located in the dotted line position shown in Fig. 1. With said lever in this position, the pin 130 is located in a position below the arm 100 so that said arm is out of range of the pin and the counter is not actuated by the oscillation of said lever.

In the operation of the mechanism, the operator, after making a numerical entry which may consist of an operation of the left hand counter alone or the right hand counter alone or both of said counters, returns the carriage to the left far enough to position the master wheel 20 to the left of the left hand register or opposite the highest denomination of this register before starting another entry. During this movement the transfer reset slide 46 of the left hand counter is actuated to oscillate the levers 108 and 118 and, assuming that the lever 118 is adjusted in operative position, the arm 100 is oscillated correspondingly to enter the count of one unit in the counter.

The counter mechanism is entirely supported upon the left hand register 22 and may be removed from the machine by the removal of the register from the rail 24. It is often desirable to count the number of entries in a certain column of the work sheet and the present counter mechanism may be employed for this purpose. For example, if it is desired to count the number of debit items on a work sheet, the left hand register 22 is located on the rail 24 in position to register the entries in this column. With the register located in this position, after an entry has been made in the register, the return of the carriage will actuate the counting mechanism of the register to count this entry.

The register 22, having the counting mechanism supported thereon, may be adjusted to any position on the rail 24 so as to count the entries in any desired column of a work sheet.

The present mechanism may also be employed to count the lines on a work sheet even though the register mechanism is then out of operation or is not used by the operator. After the carriage has moved sufficiently far to the right to

carry the master wheel 20 past the left hand register, the return of the carriage to the left far enough to actuate the transfer reset slide of the left hand register will actuate the counter mechanism to add one in the counter.

If, at any time, a line of work is undertaken in which it is not desired to count the lines of the work or the entries, the counter mechanism may be quickly and easily rendered inoperative by adjusting the lever 122 to the dotted line position shown in Fig. 1.

The counting mechanism illustrated and described in this application may be applied to existing typewriting and accounting machines with very little change in the structure of said machines. The supporting and operating mechanism for the counter is comparatively simple in construction and inexpensive to manufacture.

It is to be understood that, except as defined in the claims, the invention is not limited to the particular construction of the illustrated embodiment of the invention but that the invention may be embodied in other forms within the scope of the claims.

Having explained the nature and object of the invention, and having specifically described a construction embodying the invention in its preferred form, what is claimed is:

1. A typewriting and accounting machine having a column register, operating mechanism for the register, means for supporting the register and said operating mechanism for movement relatively in one direction to shift the operating mechanism into and out of the zone of the register and from denomination to denomination of the register and in the opposite direction to return relatively the same to starting position, a transfer mechanism for the register, a transfer reset slide operated by the relative return movement of the register and said operating mechanism, a lever oscillated by the slide, a second lever oscillated by said first lever, a counting mechanism for counting each relative movement of the register and the operating mechanism in one of said directions sufficient to carry the operating mechanism past the register, said counting mechanism being constructed and arranged to be operated by the oscillation of the second lever and a movable support for the second lever manually adjustable to move said lever into and out of operative position with relation to the counting mechanism.

2. A typewriting and accounting machine having a column register, operating mechanism for the register, means for supporting the operating mechanism and the register for relative movement in one direction to shift the operating mechanism into and out of the zone of a register and from denomination to denomination of the register and in the opposite direction to return relatively the same to starting position, transfer mechanism for the register, a transfer reset slide mounted for forward and rearward movement in the base of the register, and operated by the relative movement of the register and the operating mechanism in the latter direction, a counter mounted on the upper part of the register and having an oscillatable counting arm pivoted to swing on a horizontal axis, and means for actuating said arm from the rear end of the slide comprising a lever pivoted on a substantially horizontal axis on the rear part of the register and extending upwardly from the rear end of the slide, a connection between said lever and the slide for actuating the lever from the slide, a second lever pivoted on the

register on a substantially horizontal axis at the rear of the register and extending upwardly from said first lever, a connection between the upper end of the first lever and the lower end of the second lever for oscillating the second lever, means on the upper end of the second lever for engaging said oscillatory arm, a member mounted on the register for supporting the pivot of the second lever, and means for mounting said member for adjustment to adjust the second lever into and out of position to actuate said oscillatory arm.

3. A typewriting and accounting machine having a column register, operating mechanism for the register, means for the operating mechanism and the register for relative movement in one direction to shift the operating mechanism into and out of the zone of a register and from denomina-

nation to denomination of the register and in the opposite direction to return relatively the same to starting position, transfer mechanism for the register, a transfer reset slide mounted for forward and rearward movement in the base of the register, and operated by the relative movement of the register and the operating mechanism in the latter direction, a counting device, mounted on the register, and having an oscillatory arm and operating connections between the slide and the counting device comprising an oscillatory lever for engaging said arm having a pivot mounted for shifting movement transversely of the axis of the lever, and means for supporting said pivot for said shifting movement to locate the lever alternatively in or out of position to engage said arm.

ELMER L. WISE.
